UNITED STATES PATENT OFFICE.

BASIL W. LEACH, OF GOLCONDA, NEVADA.

ROTARY TOOTHBRAH.

1,341,916.

Specification of Letters Patent. Patented June 1, 1920.

Application filed June 30, 1919. Serial No. 307,533.

To all whom it may concern:

Be it known that I, BASIL W. LEACH, a citizen of the United States, residing at Golconda, in the county of Humboldt and 5 State of Nevada, have invented certain new and useful Improvements in Rotary Toothbrushes, of which the following is a specification.

This invention relates to brushes, and 10 more especially to those which are rotary; and the object of the same is to provide a rotary brush designed primarily for scouring the teeth, although of course it could be employed for other purposes.

15 The structure has two handles which are detachable and a brush head and staff also detachable, and all these elements may be stored within the casing, and therefore, one object of the invention may be said to be 20 the production of a device of this kind whose external parts are housed when it is out of action.

Another object is to provide means for utilizing the same casing for containing 25 tooth paste, etc., so that the whole outfit can be carried in a traveler's bag or elsewhere with safety.

Detailed description follows, reference 30 being made to the drawings wherein:

Figure 1 is a perspective view and Fig. 2 a longitudinal section of this device with its parts in position ready for service.

Fig. 3 is a plan view with the hood removed, showing the detachable parts as 35 stored within the body.

The casing is made in two parts preferably of light sheet metal such as aluminum, and comprises a body having a base plate 1 surrounded by an upstanding flange 2 and having a screw 3 depending from its center, and a hood 4 of approximately the configuration shown, having slots 5 and 6 in its front and rear ends, the hood fitting removably over and around the flange and 45 preferably secured thereto by any suitable means which will render it detachable, such as screws 7. A handle 8 has a threaded socket in its upper end for detachable engagement with the screw 3, and when this 50 handle is in place the entire casing and the parts carried thereby may be supported in the left hand.

A power shaft 10 is journaled in a post 11 rising from the center of the base plate

and also at 12 is an extension from the rear 55 end flange, beyond which bearing 12 it has a socket 13 into which may be screwed the threaded end 14 of a driving crank 15 which has a handle 16, while the inner end of said shaft 10 has a power gear 17. 60

A brush head 20 (of which there may be several in the outfit) is detachably secured in any appropriate manner at 21 to a staff 22, and the staff in turn is detachably inserted into a socket 23 at the outer end of 65 a driven shaft 24. The latter is journaled at 25 in the front end flange and at 26 in said post near its base, and carries a driven gear 27 meshing with the power gear 17.

When the parts are correctly connected 70 up for use they stand as seen in Fig. 2. The device is held in the left hand by the handle 8, and the power shaft 10 is rotated by the right hand which grasps the crank handle 16, and through the difference in size of 75 the gears 17 and 27, rapid rotation is imparted to the staff 22 and therefore to the brush head 20. The latter is inserted in the mouth and borne against the teeth, although, of course, if this device is used for 80 other purposes the element 20 whatever its character will be borne against the work. When the device is to be stored away or transported, the crank handle is unscrewed at 14 from the socket 13, the main handle 85 8 removed from the screw 3, the head 20 detached from the staff 22 and the latter removed from the socket 23, and all these parts laid upon the base plate 1 within its flange 2, after which the hood 4 is put on 90 as will be clear. The screws or other fastening devices 7 connect the two elements of the casing, and the slots 5 and 6 permit the hood to be moved vertically with respect to the sockets 23 and 13. 95

Having thus described the invention, what is claimed as new is:

A rotary tooth brush including a base plate having upstanding side, front, and rear flanges, a vertical bearing post arranged centrally upon said base plate, longitudinally extending vertically spaced parallel shafts having their inner end portions journaled through said bearing post and their outer end portions journaled through 100 said front and rear flanges, the outer portions of said shafts being formed with sockets, coacting gears mounted on the inner

portions of said shafts adjacent said bearing posts, a brush having an elongated shank connected to the socket of one of said shafts, a crank handle detachably connected to the socket of the other shaft, and a hood having depending side and end walls surrounding and detachably connected to

said upstanding flanges of the base and having slots opening out through the lower edges of their end walls and receiving the 10 extended portions of said shafts.

In testimony whereof I affix my signature.

BASIL W. LEACH. [L.S.]
